UNITED STATES PATENT OFFICE.

HENRY BLACKFORD PAYNE, OF RADFORD, COUNTY OF NOTTINGHAM, ENGLAND, ASSIGNOR OF ONE-HALF TO A. G. JENNINGS & SONS, OF BROOKLYN, NEW YORK.

WARP-KNITTING MACHINE.

SPECIFICATION forming part of Letters Patent No. 395,077, dated December 25, 1888.

Application filed January 21, 1886. Serial No. 189,238. (No model.) Patented in England December 19, 1884, No. 16,677.

To all whom it may concern:

Be it known that I, HENRY BLACKFORD PAYNE, of Radford, in the county of Nottingham, England, have invented certain new and useful Improvements in Warp-Knitting Machines, (for which Letters Patent have been granted to me in England under date of December 19, 1884, numbered 16,677,) of which the following is a specification.

10 This invention relates to an improved machine for making knitted warp fabrics, which machines are commonly known as "warp-machines," the improvements being designed with a view to simplify the construction of 15 the actuating mechanism and enable the same to be driven faster than heretofore.

The invention consists of a warp-machine which combines a needle-bar having bearded needles, a presser-bar, a point or sinker bar, 20 a fixed sley-bar, guide-bars, mechanism by which motion is imparted to the needle-bar, presser-bar, point or sinker bar, and guide-bars from a longitudinal cam-shaft, and devices for imparting endwise motion to the 25 guide-bars, as will more fully appear hereinafter, and finally be pointed out in the claims.

In the accompanying drawings, Figure 1 represents a front elevation of the machine partly broken away. Fig. 2 is a vertical cross-section on the line 1 2 of Fig. 5. Fig. 3 is a vertical cross-section on the line 3 4, Fig. 5. Fig. 4 is a vertical cross-section on the line 5 6, Fig. 5. Fig. 5 is a horizontal cross-section of a portion of the machine, the section being taken above the cam-shaft; and Fig. 6 is a plan view, partly in section, of the mechanism for actuating the guide-bars.

Similar letters of reference indicate corresponding parts.

40 In the drawings, the letter A represents the supporting-frame of my improved warp-machine, which frame preferably consists of end standards, *a a*, and one or more intermediate supports, and of one or more longitudinal tie-bars, *b b*, which connect the standards and intermediate supports.

The different parts of the machine receive motion from a longitudinal cam-shaft, C, that turns in bearings of the supporting-frame A. 50 Besides the said cam-shaft, the frame A sup-

ports in proper bearings the needle-bar rock-shaft *d*, presser-bar rock-shaft *e*, point or sinker bar rock-shaft *f*, guide-bar rock-shaft *g*, and the hand-wheel shaft *h*. The working parts of the machine consist of a needle-bar, *d'*, 55 having bearded needles *d''*, an independent presser-bar, *e'*, a point or sinker bar, *f'*, and one or more guide-bars, *g'*, all of which bars are connected by suitably-shaped levers to each of their respective rocking shafts *d*, *e*, 60 *f*, and *g*. The shaft *h*, by belt or otherwise, transmits motion to the shaft C for actuating the parts.

The needle-bar *d'* is connected with its rock-shaft *d* by means of levers *d''*, that are preferably provided with circular openings, so as to allow the cam-shaft C to pass through them. There may be any desired number of levers *d''* for supporting the needle-bar *d'*. Each of the levers *d''* is provided with rollers or contact-pieces *d'''*, that bear on the surface of suitably-shaped cams D, arranged in pairs for each lever *d''*, both of which cams are keyed to the cam-shaft C, there being two cams for each lever *d''*, as shown in Fig. 5. These cams, 70 75 by acting upon the levers *d''*, impart a vertically-reciprocating motion to the needle-bar *d'*. The relative positions and shape of these cams D are clearly shown in Fig. 3.

The presser-bar *e'* is arranged to come in 80 contact with and press the beards of the needles, and it is supported by levers *e''*, which are fastened to the rock-shaft *e*. (See Fig. 3.) Said levers *e''* each carry a roller or contact-piece, *e'''*, that bears upon a properly-shaped 85 cam, E, carried by the shaft C, as shown in Fig. 4, there being one cam E for each lever *e''*. The rollers *e'''* are pressed against their respective cams E by means of springs *e''''*, that are secured at one end to the levers *e''* 90 and at their opposite ends to the framing. As the cam E rotates the presser-bar *e'* will be alternately pressed against the beards of the needles *d''* by said cams and drawn away from said needles by the springs *e''''*.

95 The point-bar *f'* is secured to the upwardly-extending arms of elbow-levers *f''*, that are attached to the rock-shaft *f*. The ends of the lower arms of the elbow-levers *f''* carry rollers or contact-pieces *f'''*, that bear upon suitable 100

cams F, that are carried by the cam-shaft C, there being one cam F for each lever f^2 . The rollers f^4 are pressed against their respective cams F by means of springs f^7 , that are secured at one end to the levers f^2 and at their opposite ends to the framing of the machine. (See Fig. 4.) The action of the springs f^7 and cams F serves to give the sinker-bar f' through the medium of the levers f^2 a short reciprocating motion that is nearly horizontal. The point or sinker bar f' supports the points or sinkers f^8 , which are cast in leads and fastened to the bar f' . The needles d^8 pass between the sinkers f^8 , said points or sinkers acting to secure the loops formed on the bearded needles.

Just below the point or sinker bar f' there is a stationary sley, i , fixed to a bar, i' , which is supported on fixed brackets i^2 , as shown in Fig. 2. The needles d^8 pass through and rise and fall in this sley, such sley forming a bed upon which the work rests. Below and at the front of the sley i is provided a roller, j , which receives the fabric as the same is knitted by the machine.

As many longitudinal guide-bars g^3 as are required are guided in forked arms g^2 , that are attached to the ends of forward-bent levers g' , which levers are secured to the guide-bar rock-shaft g . The guide-bars g^3 are supported on the levers g' and arms g^2 by pins g^4 , that are carried by the guide-bars, which pins pass through holes in the levers g' and arms g^2 , as shown in Figs. 1, 5, and 6. The guide-bars g^3 receive endwise motion by the following means: At one end each guide-bar is secured to a spring, s , shown in Fig. 1, the opposite ends of said springs being secured to the framing. The opposite end of each guide-bar is connected by a rod, g^5 , to the upper end of a lever, g^6 , as shown in Figs. 1 and 6. The levers g^6 oscillate on the fulcrum g^7 , while their lower pointed ends bear on stud-wheels g^8 , carried by a shaft, g^9 , that is journaled to the framing.

To the circumference of the wheels g^8 are secured as many rows of studs g^9 as there are levers g^6 , one row for each lever. These studs g^9 pass into the wheels g^8 , and are secured in place by means of set-screws g^{10} , one for each stud. The studs g^9 may be of various sizes or placed at different distances apart, so as to form the different cam-surfaces required to give proper endwise motion to the guide-bars g^3 . The studs of each row act to give motion to one of the levers g^6 and one of the guide-bars g^3 . To the shaft g^9 is also keyed a worm-wheel, g^{11} , that receives motion from a worm, g^{12} , that is keyed to the cam-shaft C. As the shaft C rotates, the stud-wheel g^8 , through the gearing g^{12} and g^{13} , will be rotated. This imparts by the studs on the circumference of the same motion to the fulcrumed levers g^6 , to move the guide-bars g^3 in one direction, the springs s moving the guide-bars g^3 in the opposite direction. Said springs by their tension on the bars g^3 also act to keep the ends

of the levers g^6 pressed against the stud-wheel g^8 . By this means longitudinally-reciprocating motion is given to the guide-bars g^3 . 70

Any desired number of guide-bars and operating-levers and rows of studs may be used.

Besides the endwise motion imparted to the guide-bars g^3 by the stud-wheels g^8 and springs s they receive a backward-and-forward or laterally-oscillating motion by means of levers g^{14} , that are secured at one end to the rock-shaft g . The free ends of the levers g^{14} are forked, the end of each fork carrying a roller or contact-piece, g^{15} . Each roller g^{15} rests upon a cam, G , that is carried by the cam-shaft C. This is clearly shown in Fig. 2. As the cams G rotate, the shaft g will be oscillated by the levers g^{14} contacting said cams, thereby moving the guide-bars back and forth 85 by means of the arms g' .

The upper part of the machine is provided with a beam-tackle, K, to receive the beams of yarn K' as required to supply the needles.

The several movements of the parts are as 90 follows: The needle-bar d' rises vertically about half its motion when the lapping of the threads upon the needles is made by the guide-bars g^3 , which are moved to and fro by means of the levers g^{14} , actuated by the cams 95 G and longitudinally by the springs s and stud-wheels g^8 . The needles then rise to their full extent to pass the laps under the beards of the needles. They then descend, and just as the beards of the needles enter the points f^8 the presser-bar e' presses the beards into the eyes of the needles, and the work is then knocked over. The points f^8 then move back and forward in order to secure the last loops made. 100

The special advantages resulting from this improved construction of warp-knitting machines consist in the various motions being shortened in order to gain speed. This is accomplished by reason of the presser-bar being detached from the point-bar and having an independent motion which permits the shortening of the motion of the point-bar. The needle-bar also receives a shorter motion by reason of the presser-bar being detached 110 and carried farther back, thereby permitting a greater motion of the guide-bars. By giving independent motion to the presser-bar and point or sinker bar the double friction of the threads caused by combining the two bars in 115 one is avoided, and thus very fine silk can be used to great advantage. The needles and other parts of the machine may be arranged to work either vertically, as shown, or horizontally, or in any other position, if desired, 120 and the terms "vertical" and "horizontal" as applied to these parts are only used to render their relative positions and movements clear. 125

Having now described my invention, what I claim is— 130

1. The combination of a needle-bar having bearded needles, a separate and independent presser-bar, a point or sinker bar, a fixed sley-bar, and guide-bars, a cam-shaft having cams,

intermediate levers connecting said cams with the needle-bar, the independent presser-bar, the point or sinker bar, and guide-bars for imparting motion to said bars, and mechanism, substantially as described, for imparting longitudinally-reciprocating motion to the guide-bars, as set forth.

2. The combination of the guide-bar rock-shaft g , guide-bar levers g' , having forked arms g^2 , longitudinal guide-bar g^3 , having pins g^4 , that pass through holes in said levers and arms, whereby it is held and guided in the levers g' , fulcrumed lever g^6 , rod g^5 , connecting the guide-bar g^3 with said lever, rotary stud-wheel g^8 , having removable studs g^9 , and set-screws g^{10} , for holding said studs, worm-wheel g^{12} , and cam-shaft C, having worm g^{13} , whereby a longitudinally-reciprocating motion is given to the guide-bar, substantially as set forth.
3. The combination of the needle-bar d' , presser-bar e' , sinker-bar f' , guide-bars g^3 , and stationary sley i , with the levers d^2 , shaft d , cams D, levers e^2 , shaft e , cam E, levers f^2 , shaft f , cam F, levers g' , having forked arms

g^2 , shaft g , lever g^{14} , cams G, stud-wheel g^8 , levers g^6 , and rods g^5 between the guide-bars g^3 and said wheel g^8 , the shaft C, and means, substantially as described, between the wheel g^8 and the shaft C, for turning said wheel from 30 said shaft, all arranged for operation, substantially as herein shown and described.

4. The combination of the fixed sley with the vertically-movable needle-bar d' , having needles d^x , horizontally-movable sinker-bar f' , having sinkers f^x , horizontally-movable independent presser-bar e' , and longitudinally and laterally movable guide-bars g^3 , and mechanism, substantially as described, for moving said parts, substantially as herein shown and 40 described.

In testimony that I claim the foregoing as my invention I have signed my name in presence of two subscribing witnesses.

HENRY BLACKFORD PAYNE.
